UNITED STATES PATENT OFFICE.

JAMES L. FORBES, OF MOBILE, ALABAMA.

PUMP.

SPECIFICATION forming part of Letters Patent No. 669,628, dated March 12, 1901.

Application filed October 28, 1900. Serial No. 34,455. (No model.)

To all whom it may concern:

Be it known that I, JAMES L. FORBES, a citizen of the United States, residing at Mobile, in the county of Mobile and State of Alabama, 5 have invented a new and useful Pump, of which the following is a specification.

This invention relates to pumps, and more particularly to that class employed for raising water from deep wells, and while it is especially applicable to wells of great depth it is 10 equally operative when employed in shallow wells.

The object of the invention is to provide a construction in which a column of water will 15 be given momentum and this momentum may be employed to form a vacuum which will operate to draw the water from the well and into the tubes or tube of the pump.

In the drawings forming a portion of this 20 specification and in which similar numerals of reference designate like and corresponding parts in both the views, Figure 1 is a vertical central section of the pump and showing its position in a well. Fig. 2 is a view similar to Fig. 1 and showing a different form of 25 pump.

Referring now to Fig. 1 of the drawings, the pump comprises two cylinders 5 and 6, from the lower ends of which lead pump-tubes 30 7 and 8, extending downwardly and into the well below the level of the water. Connecting the tubes 7 and 8 and below the water-line is a pipe 9, at the ends of which are formed valve-seats 10 and 11, adapted to alternately receive a ball-valve 12, which is 35 adapted for movement longitudinally of the pipe 9. Pipes 7 and 8 extend below the pipe 9, and below their connections with the pipe 9 are formed upwardly-opening valves 13 and 40 14, the connections between the pipes 7, 8, and 9 being formed in any desired manner. Connected with the pipe 9 at its upper side and centrally thereof is an air-chamber 15, the upper portion of which is cylindrical and 45 the lower portion of which is tapered, the communicating opening between the air-chamber and the pipe 9 having a cross-section substantially equal to that of each pipe 7 and 8. In this communicating opening is formed a 50 valve-seat 16 for a ball-valve 17, which is adapted to open upwardly or away from the pipe 9. Entering through the top of the air- chamber 15 is a discharge-pipe 18, which reaches to a point below the level of the water in the well and which extends above the top of 55 the well and is provided with a hydrant 19. Upon this hydrant is fulcrumed a lever 20, one end of which is pivoted to a piston-rod 21 upon a piston 22, fitted within the cylinder 6, a similar solid piston 23 being fitted 60 in the cylinder 5 and having a rod 24, which connects with the lever 20 at the opposite side of the fulcrum from the rod 21. The lever 20 has a suitable handle 25, as shown. The operation of this form of the invention 65 is as follows: The several pipes being filled with water and the cylinder 5 being full, with the piston 23 raised and the piston 22 lowered, the valve or ball 12 will rest in the seat 11 and the ball 17 in the seat 16. If the position of the lever 20 be then reversed, the water will pass down through the pipe 7 and into the pipe 9 and thence upwardly in the pipe 8, or rather the water-pressure will be distributed in this manner. As the water- 70 pressure strikes the valve 12 the valve will move through the pipe 9 until it reaches the seat 10, when it will suddenly stop. The water passing downwardly through the pipe 7 is given a high speed, and consequently the 75 water passing through the pipe 9 has a high momentum, as has also the water which is passed upwardly through the pipe 8. When the valve 12 reaches the seat 10, the momentum of the water in the pipe 8, assisted by 80 the suction of the piston 22, tends to form a vacuum in the lower portion of the pipe 8, above the valve 13, and with the result that the valve 13 opens, and the water from the well passes into the pipe 8, and the pipe 8 85 and cylinder 6 are filled. When the valve 12 strikes the seat 10, the momentum of the water in the pipe 9 is high, and the sudden stoppage of the flow of water through the pipe 9 causes the valve 17 to rise from its seat, and 90 a portion of the water in the pipe 9 passes into the air-chamber 15 and compresses the air. When the pressure within the air-chamber 95 equalizes the inward pressure of water, the valve 17 is seated, and the expansive force of the air within the air-chamber immediately acts to establish a balance between the weight of the column of water in the pipe 18 and hydrant 19 and its own pressure,

with the result that water is forced from the mouth of the hydrant, the quantity thus forced from the hydrant being equal to the quantity forced past the valve 17. If the 5 pistons be then moved to the positions shown in Fig. 1 of the drawings, the valve 12 will pass to the valve-seat 11, with the result that the valve 14 will be opened and a second quantity of water passed into the compression-chamber 15, the apparatus having a ramming action.

In Fig. 2 of the drawings there is shown a construction comprising a cylinder 30, having a piston 31, connected with a lever 32 through the medium of a piston-rod 33. From the cylinder 30 there extends downwardly and into the well a pump-tube 34, adjacent to the lower end of which is disposed an upwardly-opening valve 35. Extending laterally from the pipe 34 and at a point above the valve 35 is an upwardly-directed elbow 36, which communicates with a cylindrical air-chamber 37 through the tapered bottom 38 thereof. At the lower end of the tapered bottom of the air-chamber is a valve-seat 39, adapted to receive a ball-valve 40, this valve having a specific gravity slightly in excess of the water, so that while it will normally lie in the seat 40, which is disposed below the 25 water-level, it may be readily forced from its seat. In practice the pump is disposed in a well to a depth sufficient to bring the water-level above the valve 40, and the pump cylinder and tube, as also the elbow and lower 30 portion of the air-chamber, are filled with water. The piston 31 being raised, the lever 32 is operated to lower the piston rapidly, when the water within the tube 34 is forced downwardly with great speed and pressure is 35 contributed to the water in the elbow 36, so that the water raises the valve 40 and enters the air-chamber and compresses the air therein, the weight of the ball-valve being such that it can be raised under the influence of the 40 inflow of water. The piston is then raised, and the elasticity of the air within the air-chamber forces the excess of water backwardly and through the elbow 36, the pressure being continued to the water in the pipe 34, which 45 is forced upwardly through the pipe with considerable momentum. While the water is passing upwardly through the pipe 34 the valve 40 suddenly enters its seat 39, and the continued upward movement of the water in 50 the pipe 34 tends to form a vacuum in the

pipe, with the result that the valve 35 is raised and an additional quantity of water enters the pipe 34. The piston is continued upwardly until it reaches a point above the spout 41, which opens outwardly through the side of the 60 cylinder 30, the result being that a quantity of water will flow from the spout.

It will be readily understood that in practice various other modifications of the invention may be made and that any desired materials and proportions may be employed without departing from the spirit of the invention.

What is claimed is—

1. In a pump for deep wells, the combination with a tube adapted to hold a column of water of a height greater than will be sustained by atmospheric pressure, a cylinder connected with the upper end of the tube and having a piston for exerting pressure in the 70 tube to give momentum to the water in the tube, an upwardly-opening valve at the bottom of the tube, a discharging air-chamber connected with the lower portion of the tube above the valve thereof for compression of the 75 air therein under the influence of the piston, a valve-seat above the first-named valve and between the tube and air-chamber, and a valve movable in the direction of the tube for engagement with the seat. 85

2. In a pump for deep wells, the combination with tubes adapted each to hold a column of water at a height greater than will be sustained by atmospheric pressure, of a cylinder connected with the upper end of each tube, 90 an upwardly-opening valve at the lower end of each tube, a pipe connecting the tubes at a point above and in close proximity to the valves, an air-chamber connected directly with the pipe between the tubes to receive 95 the entire body of discharge-water therefrom, a valve between the chamber and pipe and opening into the chamber, and a discharge-pipe leading from the air-chamber, said cylinders having pistons therein, a valve-seat in 100 the pipe at each side of the air-chamber, and a valve movable longitudinally of the pipe for engagement with said seats alternately. 105

In testimony that I claim the foregoing as my own I have hereto affixed my signature in the presence of two witnesses.

JAMES L. FORBES.
